SHOE AND OUTSOLE THEREFOR

Joseph E. Harding, Boston, Mass., assignor to
United Shoe Machinery Corporation, Flemington, N. J., a corporation of New Jersey

Application April 16, 1942, Serial No. 439,225

7 Claims.

(Cl. 12—142)

This invention relates to improvements in shoes and outsoles therefor and to improvements in methods of making shoes.

An outsole which is to be attached to a shoe by through-and-through stitches is ordinarily provided in its tread side with a marginal channel in which the sole attaching stitches are received, and a channel flap integral with the sole which is raised to open the channel for the reception of the stitches and is subsequently laid and cemented in place to close the channel and cover the stitches. The channel is usually so cut as to form a thin edge at the free outer extremity of the channel flap and the thin edge portion of the flap soon becomes worn through or disconnected from the body of the sole as the shoe is being worn and frequently the flap peels throughout the greater part of its width so that in either case an unsightly appearance is presented at the bottom of the shoe.

One object of the present invention is to eliminate the tendency of the stitch-covering flap of outsoles to peel or become disconnected from the soles.

With this object in view I provide, in the tread side of an outsole, a marginal channel so cut as to form a stitch-covering channel flap and also a lip adjacent to the free edge of the flap for overlapping the latter so as to lock the flap in stitch-covering position and thus positively to hold the flap against any tendency to peel during the wearing of the shoe. As herein illustrated, the channel is formed by two angularly disposed cuts, a relatively shallow cut extending from the tread face of the sole toward the sole edge at a substantial angle to the tread face, and a relatively deep cut extending inwardly from the bottom of the shallow cut in a plane substantially parallel to the tread face. The shallow cut forms a beveled edge at the free outer extremity of the channel flap and it also forms a lip having an undercut side or shoulder, opposite to the beveled edge of the channel flap, which is adapted to engage and overlie the edge of the flap when the flap is in position to close the channel and which thus serves most effectively to hold or lock the flap in place and to protect the edge of the flap from wear. The invention is not limited, however, to the provision of a channel flap and a locking lip by the making of channel cuts of the particular form and arrangement just described, it being essential only that the lip be adapted to overlap the edge portion of the channel flap when the latter is in stitch-covering position.

Invention is also to be recognized in certain

novel features of construction embodied in a shoe in which my improved outsole is incorporated and in improvements in methods of making such shoes.

The invention will now be explained with reference to the accompanying drawing, in which

Fig. 1 is a perspective view of an outsole embodying my invention, the view showing the tread side of the outsole;

Fig. 2 is a fragmentary sectional view on an enlarged scale taken along the line II—II of Fig. 1;

Fig. 3 is a fragmentary sectional view on an enlarged scale of a shoe embodying my improved outsole, the outsole being shown as it appears after the channel flap and the flap-locking lip have been raised to open the stitch-receiving channel;

Fig. 4 is a view similar to Fig. 3 but showing the shoe as it appears after the channel flap has been laid and the lip has been set in position to lock the flap in place, and showing also an edge setting tool in operative position to set the edge of the outsole and to lay the lip in flap-locking position;

Fig. 5 is a view similar to Fig. 4 but showing a modified arrangement of the channel flap and the flap-locking lip;

Fig. 6 is a fragmentary cross-sectional view of an outsole illustrating a channel flap and lip construction embodying a further modification of my invention, the flap and the lip being shown as they appear before being raised; and

Figs. 7 and 8 are fragmentary cross-sectional views of a shoe having an outsole provided with a channel flap and a flap-locking lip of the types shown in Fig. 6, the flap and the lip being shown in raised positions in Fig. 7 and in positions to close the channel and lock the channel flap in Fig. 8.

In preparing an outsole 10 in accordance with my invention as illustrated in Figs. 1 and 2, I form in the tread face 12 of the sole a marginal channel 14 by making two angularly disposed cuts 16 and 18 (Fig. 2), the cut 16 being relatively shallow and extending from the tread face toward the sole edge at an angle of approximately 30° to the tread face and terminating a short distance from the sole edge, and the cut 18 being relatively deep and extending inwardly from the bottom of the cut 16 in a plane substantially parallel to the tread face. Preferably, also, I form a stitch-receiving groove 20 in the body of the sole, the groove being located relatively to the channel cut 18, as shown in Fig. 2.

The channel cuts 16 and 18 and the groove 20 may be formed progressively along the margin of the sole by the use of a conventional channeling machine of the type disclosed, for example, in United States Letters Patent No. 1,668,081, granted May 1, 1928, upon application of W. C. Meyer, such a machine being fitted with a channeling knife suitably shaped to make the channel cuts 16 and 18 and with the usual grooving tool. The cutting of the channel 14 results in the formation of a channel flap 22 which serves to cover and protect the outsole-attaching stitches which are to be received in the groove 20. Inasmuch as the channel cut 16 is inclined to the tread face of the sole, as shown, the channel flap 22 is formed with a beveled outer or free edge 24 which slopes outwardly from the outer side to the inner side of the flap, and a lip or rib 26 is formed opposite to the beveled edge of the flap 22, the lip 26 having an undercut side or face 28 forming a shoulder which is complementary to the beveled edge face 24 of the flap 22. The channel 14 may be formed by a knife so constructed that it will operate to cut the channel without raising either the channel flap 22 or the lip 26, in which case the flap and the lip will appear substantially as shown in Figs. 1 and 2 when the channeling has been completed. On the other hand, the channeling knife may be so constructed and arranged as to raise the channel flap, or to raise both the channel flap and the lip, as the channel is being cut so as to open the channel and expose the groove 20 for the reception of the stitches which are to attach the sole permanently to the shoe. Usually, however, it is desirable to lay the sole and attach it temporarily by means of cement to the shoe bottom before the sole is permanently attached by means of stitches and, consequently, it is considered preferable to cut the channel without raising either the channel flap or the flap-locking lip into upstanding positions where they would interfere with the operation of the pad or presser member of the sole laying machine. Accordingly, after the sole has been channeled and before the channel has been opened, the sole is laid on the bottom of a shoe which, as shown in Fig. 3, may comprise an insole 30 and an upper 32 the margin of which is secured in overlasted position upon the insole by means of staples 34. Thereafter, the channel flap 22 and the lip 26 are raised into the upstanding positions shown in Fig. 3. This may be accomplished by hand operations or by the use of a channel opening machine having a plow-like channel opening device shaped to raise both the channel flap and the lip. As indicated in Fig. 3, the lip 26 is raised by forcing or deflecting it outwardly until its beveled or undercut inner side or shoulder 28 is substantially perpendicular to the channel cut 18 and to the tread face of the outsole.

The outsole is then permanently attached to the shoe by means of through-and-through stitches, such as the lock-stitches shown at 36, the stitches being received in the groove 20 and passing through the body of the outsole and through the upper 32 and the insole 30. A coating of cement is preferably applied to the bottom of the channel 14 and to the inner sides of the flap 22 and the lip 26 and the flap 22 is laid into the position shown in Fig. 4 to close the channel and cover the stitches. Thereafter, the lip 26 is laid into position to overlap the beveled edge 24 of the flap 22. The cement will secure the flap

and the lip permanently in place with the lip overlapping the beveled edge 24 of the flap 22 and positively locking the flap in stitch-covering position. The laying of the flap 22 and the lip 26 may be accomplished by the use of suitable hand tools or a conventional channel flap laying machine may be employed for the purpose, it being necessary only to operate the machine so that the laying of the flap 22 will take place somewhat in advance of the laying of the lip 26.

It is considered preferable to lay the lip 26 in the process of performing the customary edge finishing and edge setting operations upon the outsole. For this purpose it is usual to employ an edge setting tool having a work-engaging face shaped to impart a beaded or otherwise ornamental configuration to the sole edge. Such a tool is indicated at 40 in Fig. 4 as operating upon the edge of the outsole, the tool, as shown, being shaped to form beads or ridges 42, 42 upon the edge of the sole. For the purpose of laying the lip 26 in flap-locking position, the tool 40 is provided also with a beveled face 44 arranged to engage the lip while the latter is in the raised or deflected position shown in Fig. 3, and to force the lip inwardly and downwardly until its inner face is restored substantially to its initial position wherein it will overlie and engage the beveled face 24 of the channel flap 22. The face 44 of the edge setting tool also compresses and consolidates the sole material constituting the lip 26 and forms a corresponding beveled face at the outer side of the lip. It will be noted that the beveled face 44 extends from the sole edge inwardly to the outer edge of the channel flap so that, in the finished sole, the channel flap actually extends to the outer extremity of the tread surface of the sole. Thus the appearance of the shoe bottom will not be marred by the presence of a channel cut spaced inwardly from the sole edge as would be the case in the absence of the beveled surface 44.

Instead of cutting the stitch-receiving channel as above described so that the channel flap will be connected along its inner extremity with the body of the sole and will have a free outer edge, the channel may be cut, as shown in Fig. 5, so as to provide a channel flap 220 connected at its outer extremity with the sole and having a free inner edge which is beveled and overlapped by the correspondingly beveled or undercut face of a lip 260 formed by the channel in the body portion of the sole. It will be noted that whether the stitch-receiving channel is cut as shown in Fig. 5 or as shown in Fig. 2 the beveled edge of the flap formed by the channel will slope from the tread side of the outsole away from the base or root of the flap so that when it is covered by the undercut face of the lip 26 or the lip 260, as the case may be, the lip will lock the channel flap in stitch-covering position. By cutting the channel so as to form the channel flap and the flap-locking lip, as shown in Fig. 5, the sole attaching stitches 36 may be sewn much nearer the edge of the sole than is usually practicable in shoes the soles of which are attached by through-and-through stitches with the resulting advantage that a so-called close edge shoe is produced having an exceptionally tight joint between the upper and the outsole and one which will not tend to open up during the wearing of the shoe.

A stitch-receiving channel of a still further modified form is shown in Figs. 6 to 8. As best indicated in Fig. 6, this channel is formed by

a straight cut 46 in the tread face 18 which slopes outwardly toward the sole edge, a straight cut 48 which slopes inwardly from the outer extremity of the cut 46, and a curved cut 50 which extends inwardly from the inner extremity of the cut 48 and which, as shown, may terminate in a stitch-receiving groove 200. The cuts 46, 48 and 50 combine to form a stitch-covering channel flap 320 and a flap-locking lip 360, the channel flap having an outer portion of substantial width which will be buried beneath the lip 46 when the channel flap has been laid in stitch-covering position as shown in Fig. 8 so that the outer portion of the channel flap will not only be locked in place by the lip but will be protected from wear to an even greater extent than are the lips shown in the other figures. The channel flap 320 and the lip 360 may be readily raised to upstanding positions, as shown in Fig. 7, to open the channel for the reception of the sole attaching stitches. Thereafter, when the channel flap is laid to cover the stitches the lip 360 will be deflected inwardly and downwardly into position to overlap the edge portion of the channel flap so as to lock the flap in place and protect its edge portion from wear. It will be noted that while the edge face only of the channel flap is overlapped by the locking lip in the constructions illustrated in Figs. 1 to 5, inclusive, the construction illustrated in Figs. 6 to 8 provides for the locking of the channel flap by a lip which overlaps not only the edge but also a substantial portion of the outer side of the channel flap. Thus, particularly when cement is used, as preferred for securing the flap and the lip in their final positions, these parts will be permanently held in place and the outer margin of the channel flap will not be subjected to any wear until after the locking lip has become practically worn away.

Having described my invention, what I claim as new and desire to secure by Letters Patent of the United States is:

1. An outsole having in its tread side a marginal stitch-receiving channel forming a stitch-covering flap, and a flap-locking lip, said flap having an outer face continuous with the tread face of the sole and said lip having an undercut face adapted to engage the free edge of said flap to lock said flap in stitch-covering position.

2. An outsole having a marginal channel in its tread side forming a channel flap for covering outsole-attaching stitches to be received in said channel, and a lip for locking the stitch flap in stitch-covering position, said flap having a beveled edge face and an outer lateral face continuous with the tread face of the sole and said lip having a beveled face for engaging the beveled face of said flap to lock the flap in stitch-covering position.

3. An outsole having a marginal channel in its tread side forming an inner channel flap for covering outsole-attaching stitches to be received in the channel, and an outer flap-locking lip, said flap having a beveled outer edge and said lip

having a correspondingly beveled inner edge for engaging the beveled edge of the flap to lock the flap in stitch-covering position.

4. A shoe comprising an insole, an upper having its lower margin secured in overlasted position upon said insole, an outsole having a marginal channel in its tread side forming a channel flap having an outer face continuous with the tread face of the outsole and having a beveled edge face sloping from the tread side of the outsole away from the root or base of the flap, stitches extending through the insole, the upper and the outsole and securing said parts together, said stitches lying in said channel and being covered by said channel flap, and a lip formed in the outsole by said channel, said lip having an undercut face overlapping the beveled edge of said flap and locking the flap in stitch-covering position.

5. A shoe comprising an insole, an outsole, an upper having an inturned margin interposed between the insole and the outsole, and through-and-through stitches securing said parts together, said outsole having in its outer side a marginal channel forming a flap at one side of the channel and a lip at the other side of the channel, said stitches lying in said channel and being engaged and covered by said flap and said lip having an undercut face overlying the edge of said flap and locking the flap in stitch-covering position.

6. A shoe comprising an insole, an upper having its lower margin secured in overlasted position upon said insole, an outsole having a marginal channel in its tread side formed by a cut sloping from the tread face of the outsole toward the sole edge and a second cut extending inwardly from the bottom of the first cut, a channel flap formed by said channel, said flap having an outer face flush with and constituting a portion of the tread face of the outsole and having a beveled edge face sloping outwardly from said outer face, stitches extending through the insole, the upper and the outsole and securing said parts together, said stitches lying in said channel and being covered by said channel flap, and a lip formed by said channel, said lip having an undercut face overlying the beveled edge face of said channel flap and locking said channel flap in stitch-covering position.

7. That improvement in methods of making shoes which consists in providing an outsole having in its tread side a marginal channel forming an inner flap having a beveled outer edge and an outer lip having a correspondingly beveled inner edge, raising said flap and said lip thereby opening said channel, securing said outsole to a shoe by stitches received in said channel, laying said flap into position to cover said stitches, setting the edge of the outsole, and in the course of the edge-setting operation laying said lip with its beveled edge in overlying relation to the beveled edge of said flap and thereby locking said flap in stitch-covering position.

JOSEPH E. HARDING.
